Attorney

UNITED STATES PATENT OFFICE.

ALBERT A. HOWE, OF TERRILL, IOWA.

NURSERY-SEAT.

1,339,891.

Specification of Letters Patent. Patented May 11, 1920.

Application filed August 18, 1919. Serial No. 318,363.

To all whom it may concern:

Be it known that I, ALBERT A. HOWE, a citizen of the United States, residing at Terrill, in the county of Dickinson, State of Iowa, have invented certain new and useful 5 Improvements in Nursery-Seats; and I do hereby declare the following to be a full, clear, and exact description of the invention, such as will enable others skilled in the art to which it appertains to make and use 10 the same.

This invention relates to an improved nursery seat or children's toilet seat, and the object thereof is to provide an improved 15 simple and novel arrangement of foldable parts adapted to form a bottom, a back and arms. In addition a tie strap is provided to prevent escape of the occupant, said tie strap being designed to be used as a handle when the device is folded into a compact 20 form for a carriage or for disposition within a suitcase for transportation or travel.

A further object of the invention is to provide a device of the character specified in which the back and arms are foldable 25 toward the seat bottom or capable of being rigidly and substantially held in upright positions, the back being provided with means for engaging the arms for this purpose, while means are provided on the back 30 to secure the arms or sides in folded relation to the bottom, the arms in addition having tie strap engaging means so as to form a barrier at the front of the seat when in use, said engaging means being designed 35 to extend through an opening in the back when the device is folded so that the tie strap can be used as a handle.

With the above objects and others in view 40 as will appear as the specification proceeds, the invention comprises certain novel combinations and arrangements of parts as will be hereinafter more particularly pointed out and claimed.

Reference is had to the accompanying 45 drawings forming a part of this application, wherein like characters designate corresponding parts throughout the several views, in which—

Figure 1 is a plan view of the improved 50 nursery seat;

Fig. 2 is a side elevation;

Fig. 3 is a front elevation;

Fig. 4 is a plan view of the device folded, 55 and Fig. 5 is a bottom view of the folded device, showing the use of the handle for carrying it.

Referring to the drawings in detail, the numeral 10 designates the bottom member preferably formed of a flat board and provided with the usual opening 11 of suitable size and convenient form. Secured on top 60 of the bottom 10 adjacent to its rear edge is a strip 12 to which is hinged a back 13 as shown at 14 so that it may be swung to an upright position or folded against the bottom. 65

Secured to the side edges of the bottom are strips 15 which form bindings for the edges and which project upwardly a distance equal to twice the thickness of the back or its strip 12 so as to accommodate 70 therebetween, in a manner to lie flush with their upper edges, the arms or sides 16 which are hinged to the strips 15 as shown at 17 in a manner to fold to upright position or downward and inward into alignment with each other. The arms 16 are preferably cut out as shown at 18 to accommodate pivoted hooks 19 carried by the back 13 adjacent the side edges thereof as well as to permit said parts to properly fold, in addition to providing a graceful design and reducing the weight of the device. 75

The rear ends of the arms 16 are cut out as shown at 20 to accommodate the hinges 14, and the upper edges of the arms adjacent to 80 their rear ends are notched vertically as shown at 21 so that when the arms are opened upwardly to upright positions and the back is raised therebetween, the hooks 19 may be engaged with the notches and 85 thus not only brace the back in an upright position but securely hold the arms in proper relation to form the seat structure. Disposed at the inner sides of the arms are 90 suitable eyes 22 designed to be engaged by snap hooks 23 at the ends of a tie strap 24 in order to form a barrier to prevent escape 95 of the occupant.

When the device is folded, the back is disposed against the bottom flush with the 100 strip 12 and the arms or sides are folded down onto the back, the hooks or detachable fasteners 19 having been previously disengaged from the arms. The eyes 22 then extend through an opening 25 formed at a 105 proper place in the back so that the strap will project through the opening 11 and form a handle by which the device may be carried. In their folded relation the arms are held upon the back, and for this purpose the arms when so folded are disposed in 110 spaced relation to accommodate a vertical

strip 26 which is secured to the back and carries a turn button 27 designed to span the arms. In this position of the turn button, the arms will be held in collapsed relation 5 upon the back and the latter upon the bottom, while alinement of the turn button with the strip will permit the seat to be arranged in operative form. The device may also be attached to an ordinary toilet seat or 10 bowl by means of a movable fastener 28 consisting of an angular metallic arm formed of a horizontal portion notched as shown at 29 to engage a headed stud 30 depending from the bottom at the rear thereof adjacent 15 to the opening 11 the arm having its free end curved slightly upward to resiliently grip the part to which the device is attached.

It will thus be seen that the device can be easily and quickly applied and when so applied will be securely held in position and that it is especially desirable when traveling. It will also fold compactly and is therefore very easily transported.

It is of course to be understood that the 25 folding arrangement provided in connection with the back and arms, may be employed in connection with any form of seat or chair, or settee, especially in conjunction with the arrangement of connecting the back and 30 arms to hold the same in operative positions.

What is claimed is:—

1. A folding seat structure comprising a bottom, a back hinged to the bottom, said back having an opening therethrough, arms 35 hinged at the sides of the bottom, means for fastening the parts when opened up, and a strap connecting the arms and adapted to extend through said opening to form a handle when the parts are folded.

2. A nursery seat comprising a bottom, a 40 toilet seat engaging device carried by the bottom, a back hinged to the bottom, arms hinged at the sides of the bottom, said back having an opening therethrough, and a tie strap connecting the arms and adapted to extend 45 through the opening of the back to form a handle when the parts are folded.

3. A nursery seat comprising a bottom having an opening, a back hinged to the bottom and having an opening adapted to register 50 with the opening therein when the back is folded, arms hinged at the sides of the bottom and foldable onto the back when the back is folded onto the bottom, means to hold the parts folded, means to hold the 55 back and arms in upright positions, eyes in the inner faces of the arms, and a tie strap connecting said eyes, said eyes and strap being adapted to project through said openings when the device is folded.

4. A nursery seat comprising a bottom having an opening, a back hinged to the bottom and having an opening adapted to register with the opening therein when the back is folded, arms hinged at the sides of the 65 bottom and foldable onto the back when the back is folded onto the bottom, means to connect the back and arms when in upright positions, eyes in the inner faces of the arms adapted to project through said openings 70 when the device is folded, and a strap having hooks to be engaged with said eyes.

In testimony whereof I affix my signature in the presence of two witnesses.

ALBERT A. HOWE.
